CLAIM

The ornamental design for a display screen or portion thereof with graphical user interface, as shown and described.

DESCRIPTION

FIG. 1 is an image of a display screen or portion thereof with graphical user interface in accordance with the present invention;

FIG. 2 is another image thereof;

FIG. 3 is another image thereof;

FIG. 4 is another image thereof;

FIG. 5 is another image thereof;

FIG. 6 is another image thereof;

FIG. 7 is another image thereof;

FIG. 8 is another image thereof; and,

FIG. 9 is another image thereof.

The outermost dashed broken lines depict a device and a display screen or portion thereof forming no part of the claimed design. The remaining dashed broken lines depict portions of the graphical user interface forming no part of the claimed design. The dashed and dotted broken lines depict a symbolic break in length of the graphical user interface and the portion of the display screen between the break lines forms no part of the claimed design.

The appearance of the display screen or portion thereof with graphical user interface sequentially transitions in a first embodiment between the images shown in FIG. 1 to FIG. 2 to FIG. 3 to FIG. 4 to FIG. 5 to FIG. 6 to FIG. 8 to FIG. 9 in a first sequence; sequentially transitions in a second embodiment between the images shown in FIG. 1 to FIG. 2 to FIG. 3 to FIG. 7 to FIG. 8 to FIG. 9 in a second sequence; sequentially transitions in a third embodiment between the images shown in FIG. 1 to FIG. 2 to FIG. 3 to FIG. 4 to FIG. 5 to FIG. 7 to FIG. 8 to FIG. 9 in a third sequence; and sequentially transitions in a fourth embodiment between the images shown in FIG. 1 to FIG. 2 to FIG. 3 to FIG. 4 to FIG. 5 to FIG. 7 in a fourth sequence. The process or period in which one image transitions to another forms no part of the claimed design.
